SLIPPER OR SIMILAR ARTICLE

Hyman Singer, New York, N. Y.

Application August 24, 1950, Serial No. 11,899

Term of patent 3½ years

(Cl. D7—7)

To all whom it may concern:

Be it known that I, Hyman Singer, a citizen of the United States of America, residing in New York city, county of Kings, and State of New York, have invented a new, original, and ornamental Design for a Slipper or Similar Article, of which the following is a specification, reference being had to the accompanying drawing, forming part thereof, wherein,

Figure 1 is a front perspective view of a slipper, showing my new design.

Figure 2 is a side elevational view of same, and

Figure 3 is a bottom plan view of the slipper shown in Figures 1 and 2.

The essential features of my design for a slipper reside in the specific type of ornamentation and the manner in which it is placed at the inter-

section of the stitching as shown on the vamp and the heel strap in combination with the zig-zag lines of stitching as seen most clearly in Fig. 3.

I claim:

The ornamental design for a slipper or similar article, substantially as shown and described.

HYMAN SINGER.
